UNITED STATES PATENT OFFICE.

JACQUES SCHLUMPF, OF OBER-WINTERTHUR, SWITZERLAND.

MACHINE FOR TREATING YARNS IN HANKS WITH LIQUID.

Application filed June 3, 1924. Serial No. 717,630.

To all whom it may concern:

Be it known that I, JACQUES SCHLUMPF, a citizen of the Swiss Confederation, residing at Ober-Winterthur, Rychenbergstrasse 207, Canton Zurich, Switzerland, have invented new and useful Improvements in Machines for Treating Yarns in Hanks with Liquid, of which the following is a specification.

The present invention relates to that of machines for continuously dyeing, washing and otherwise similarly treating yarn in hanks, in which a concentric series of tanks or vats have rotating above them a concentric series of pairs of rollers upon and between which the hanks are suspended. By the rotation of the rollers upon their axes the hanks are continuously run through the liquor in the troughs or vats below, and by the concentric motion of the rollers the hanks are successively transferred from one vat to the next through the series.

In such machines one of the rollers of one pair, the one carrying the hanks is pressed by suitable devices against the second roller of a pair which is driven by suitable gearing from a motor. The roller carrying the hanks is driven by friction at the same time the liquid is squeezed out of the yarn which runs in and out of the vat.

According to the present invention means are provided to adjust simultaneously and uniformly the pressure exerted on the yarn and to prevent any excess of pressure. Moreover means are provided to part the rollers at certain points of their circular path to take-off and replace the hanks.

In the accompanying drawings one form of construction is shown by way of an example.

Fig. 1 is a sectional elevation of the machine;

Fig. 2 is a top view of a part of the machine;

Figs. 3, 4 and 5 show a pair of rollers in different positions;

Fig. 6 illustrates is a diagrammatical manner the working of the machine.

The machine shown comprises a circular series of vats 1 having radial walls or divisions 1^a separating adjacent vats. Above the vats 1 a series of pairs of rollers 13, 21 is arranged on a frame 12 rotatably mounted in a stationary frame 6. The frame 12 is

intermittently rotated by means of a gear 2 (forming the object of a separate application). Said gear 2 comprises a bevel wheel 3 meshing with a bevel gear 4 keyed on a vertical shaft 5. Shaft 5 is rotatably mounted in a stationary sleeve 18 of the frame 6 and carries at its upper end a bevel wheel 7. Said bevel wheel 7 engages a bevel wheel 8 rigidly fixed to the boss of a bevel gear 9 on a shaft 10. The shaft 10 runs in radial direction and is rotatably mounted in bearings 11 of the frame 12. The bevel gear 9 engages similar bevel gears 9 of adjacent shafts 10 which are all arranged in radial directions at equal distances apart each shaft 10 driving the next following by its bevel gear 9. On the sleeve 18 of frame 6 a spur wheel 17 is rotatably mounted which is in mesh with a spur wheel 16 keyed to vertical shaft 15. The latter is driven by means of a bevel gear 14 by the gear 2. Rigidly fixed to the said spur wheel 17 is the frame 12 which is supported by rollers 19 journaled on pins 20 of the frame 6. The frame 12 supports the bearings 11 for the shafts 10. On each shaft 10 a roller 13 for instance of rubber is rigidly fixed. Cooperating with each roller 13 is a roller 21 loosely mounted on a shaft 61. The roller 21 and the shaft 61 run parallel to roller 13 and shaft 10. The shaft 61 is rigidly fixed to an arm 22 of a sleeve 62 rotatably mounted on a shaft 44 which shaft 44 is held fast in the frame 12. On the sleeve 62 a spur wheel 43 is fastened which is in mesh with a toothed segment 42 rotatably mounted on the shaft 42. The said segment 10 is provided with a downwardly projecting nose 41 which nose 41 strikes against cams 39 adjustably mounted on the frame 6 as soon as the frame 12 is rotated by the said gear 2. If nose 41 strikes against a cam 39 the segment 42 rotates on shaft 10 and rotates the sleeve 62 by means of the spur wheel 43. The arm 22 and therewith shaft 61 and roller 21 is swung out (Fig. 5). The rollers 13 and 21 are moved apart and hanks A of yarn may be placed on the roller 21. As soon as nose 41 has passed the cam 39 the roller 21 falls down by its own weight and the yarn hung thereon is brought in contact with the roller 13 (Fig. 105 6). Each time a pair of rollers 13, 21 passes

from one vat to the adjacent vat the roller 21 may be lifted to pass the hanks A clear over the partition walls.

To press the roller 21 on to the roller 13 to press-off the liquid in the hanks A a double armed lever 23, is rotatably mounted on the shaft 61. One arm 25 thereof projects downwardly, the other arm rests on a slanting plane 38 of a double armed lever 26, 27 rotatably mounted on a vertical shaft 28. On the frame 6 cams 51 are adjustably mounted which project in the path of the lower end of arm 25. If the frame 12 rotates the arm 25 strikes 15 against the cams 51 (Fig. 3) the lever 24 rotates on shaft 61, and the upper arm 24 slides along the slanting plane 38 rotating thereby the lever 26, 27 on its shaft 28 against the action of a spring 31. The 20 spring 31 is interposed between a rod 29 linked to arm 27 and the bars 30 linked by a bolt 34 to the rim of a sleeve 33. Said sleeve 33 is rotatably mounted in the upper wall 32 of the frame 12. A lever 35 is fastened to the upper face of the sleeve 33, the free end of said lever 35 is bifurcated and embraces a nut of a screw-threaded spindle 37. A hand wheel 36 is fixed to said spindle 37 which is attached to a pivot 25 mounted on wall 32. On turning the wheel 36 the nut is moved on it and the sleeve 33 is rotated compressing or releasing simultaneously the springs 31 of all the 30 levers 26, 27. The pressure exerted by said springs 31 on the lever 26, 27 and on the roller 21 (if the lever 24, 25 has been turned on its pivot 61) may be varied by rotating the sleeve 33, as the levers 26, 27 offer more or less resistance against turning by arm 24 35 according to the pressure of the spring 40 exerted on it. If the arm 22 is raised (Fig. 5) the arm 24 moves along an extension 45 of the arm 26.

The machine works as follows:

The frame 12 with the pairs of rollers 13, 21 is intermittently advanced in such a manner that the pairs of rollers remain some time above one vat. The hanks on the rollers 21 are turned as soon as they are 50 pressed against the power-driven roller 13 by the roller 21. The liquid in the hanks is squeezed-off as soon as arm 25 passes on the cam 51. The parts of the machine are 55 adjusted in such a manner that the arm 25 rests on the corresponding cam 51 when the frame 12 comes to rest after an advance while the roller 13 is rotating. The hanks are turned and pass through the liquid of a vat the liquid is continuously squeezed-off. The gear 2 is constructed in such a 60 manner that the direction of rotation of the rollers 13 is reversed each time the frame 12 is advanced. This change of direction of rotation is taken recourse to in order to 65 prevent that the individual threads of the

skeins or bundles get tangled up. Experience has shown that if a cord or yarn is held under tension in the same direction for considerable time, that is, if it is under a rotary strain, some of the threads are advanced more rapidly than others. The threads of the yarn, therefore, get tangled up and the yarn becomes useless. It is quite well known, and not claimed as novel in the present application, to change periodically the direction of movement of the device. The yarn is being moved for a certain period in one direction and for the same period in the opposite direction. The hanks A move alternately in opposite directions in two consecutive positions and are kept in good order. While the hanks A pass from one vat to the other the roller 21 is raised by the cams 39 and gears 42, 43 as described and the hanks A remain at rest. After the 85 hanks A have passed all the vats they may be taken-off, a cam 39 being provided to lift the roller 21 from roller 13 at this point.

The number of pairs of rollers and the 90 number of vats may be varied according to requirement.

What I wish to secure by U. S. Letters Patent is:

1. A machine for continuously dyeing, 95 washing or otherwise similarly treating yarn in hanks, comprising a series of vats arranged in a circle, a series of pairs of rollers travelling above said vats, means to intermittently advance the said pairs of 100 rollers, means to rotate one roller of each pair alternately in different directions, means to bring the second roller of a pair in and out of engagement with the power driven roller, means to press the rollers 105 against each other.

2. A machine for continuously dyeing, 110 washing or otherwise similarly treating yarn in hanks, comprising a series of vats arranged in a circle, a series of pairs of rollers travelling above said vats, means to intermittently advance the said pairs of rollers, means to rotate one roller of each pair alternately in different directions, means to bring the second roller of a pair in and out of engagement with the power driven roller, means to press the rollers 115 against each other said means comprising an elastic abutment, and a lever mounted 120 on the roller shaft.

3. A machine for continuously dyeing, 125 washing or otherwise similarly treating yarn in hanks, comprising a series of vats arranged in a circle, a series of pairs of rollers travelling above said vats, means to intermittently advance the said pairs of rollers, means to rotate one roller of each pair alternately in different directions, means to bring the second roller of a pair in and out of engagement with the power 130

driven roller, a lever mounted on each of the hank carrying roller shafts, an abutment for each pair of rollers, springs acting on each abutment, means to tension and release simultaneously all the springs of all the abutments, and means to engage said lever.

4. A machine for continuously dyeing, washing or otherwise similarly treating 10 yarn in hanks, comprising a series of vats arranged in a circle, a series of pairs of rollers travelling about said vats, means to intermittently advance the said pairs of rollers, means to rotate one roller of each 15 pair alternately in different directions, means to bring the second roller of a pair in and out of engagement with the power driven roller, a double armed lever (23) rotatably mounted on the shaft of each 20 hank-carrying roller (21), a double armed lever (26, 27) for each roller (21) a slanting face on said lever (26, 27) against which arm (24) rests a spring (31) for 25 each lever (26, 27) means to simultaneously tension all the springs, cams (51) arranged in the way of the arms (25) adapted to

press the arm (24) against the yielding member (38, 26, 27) substantially as described.

5. A machine for continuously dyeing, 30 washing or otherwise similarly treating yarn in hanks, comprising a series of vats arranged in a circle, a series of pairs of rollers travelling above said vats, means to intermittently advance the said pairs of 35 rollers, means to rotate one roller of each pair alternately in different directions cams (39) mounted on the rigid frame (6) of the machine, a toothed segment (42) journalled on the power driven roller (13), a toothed 40 gear (43) meshing with said toothed segment, an arm (22) rigidly connected to said gear (43), a hank carrying roller (21) rotatably mounted on said arm, running parallel to said roller (13), a nose (41) engaging said cams (39), means to yieldingly 45 press the roller (21) against the power driven roller (13) all as described and for the purpose set forth.

In witness whereof I affix my signature.

JACQUES SCHLUMPF.
